UNITED STATES PATENT OFFICE.

ANDREW J. WATKINS, OF LYON, MONTANA.

BULLET.

1,114,205.

Specification of Letters Patent. Patented Oct. 20, 1914.

Application filed January 8, 1912. Serial No. 670,067.

To all whom it may concern:

Be it known that I, ANDREW J. WATKINS, a citizen of the United States, residing at Lyon, in the county of Madison and State 6 of Montana, have invented a new and useful Bullet, of which the following is a specification.

This invention relates to bullets of the expanding or mushroom type.

10 Expanding or mushroom bullets, as heretofore constructed, are open to the objection that the expansion or distortion of the bullet causes it to lose its penetrating qualities and shape.

15 The principal object of the present invention is to overcome the foregoing objections and to provide a bullet which will preserve its penetrating point as well as its normal shape and distribution of weight, while at 20 the same time providing an expansible portion which will serve the function usually performed by the mushrooming or distortion of the head of the ordinary soft-nose bullet.

25 With the foregoing and other objects in view, which will appear as the description proceeds, the invention resides in a bullet characterized by the features hereinafter described and claimed, it being understood that 30 changes in the forms of bullet illustrated in the accompanying drawing may be made within the terms and scope of what is claimed without departing from the spirit of the invention.

35 In the accompanying drawing forming part of this specification, —Figure 1 is a side elevation of a bullet constructed in accordance with the present invention; Fig. 2 is a longitudinal section through the completed bullet showing the two-part jacket and filler; Fig. 3 is a longitudinal section through the two-part jacket with the parts shown in separated relation, the 40 filler being omitted; Fig. 4 is an enlarged 45 detail view showing in longitudinal section the overlapping portions of the two-parts of the jacket; Fig. 5 is a view similar to Fig. 4 showing the fore end of the rear part of the jacket; Fig. 6 is a view similar to Fig. 4 showing the fore end of the rear part of the jacket in expanded condition, the remaining portions of the bullet retaining their normal shape and their normal 50 distribution of weight, whereby to preserve 55 the penetrating qualities of the bullet to the maximum degree after expansion; Fig. 7 is

a view similar to Fig. 2, showing a modified form of the invention. Fig. 8 is a view similar to Fig. 4 of the modified construction illustrated in Fig. 7.

The bullet forming the subject matter of the present invention comprises a jacket or casing 1 having therein a filler 2 formed from any suitable material. I prefer to use lead or metal of substantially the same 60 characteristics, as it can be melted and poured into the jacket 1 through the filler opening 3 at the rear end thereof. The jacket 1 preferably is made up of two parts, namely, a rear part 4 and a fore part 5. 65 The fore end 6 of the rear part 4 preferably overlaps the outside of the rear end 7 of the fore part 5, as shown clearly in Figs. 2 and 4 of the drawing, and said fore end 6 of the rear part 4 is internally beveled to 70 a sharp edge, as indicated at 8. The fore part 5, as shown best in Fig. 3, is formed externally with an annular rib 9 and the beveled end 8 of the fore end 6 is crimped or bent around the outstanding rib 9 as 75 shown clearly in Fig. 2. The rib 9 has a two-fold function in that, first, it serves normally to lock the two sections of the jacket together, and, second, it serves to dispose the crimped forward edge 8 of the 80 part 4 a sufficient distance away from the surface of the penetrating point of the bullet to insure that the expanding action of the fore end 6 will be started and then continued to the position shown best in Fig. 6 85 of the drawing.

For the purpose of preventing the fore end 5 from telescoping within the rear end 4 at the moment of the impact or penetration, and of insuring that the filler 2 and the 90 rear part 4 will not separate or part company at the moment of the expansion of the fore end 6, an internal rib 10 is provided in the rear part 4 of the jacket, as best shown in Fig. 5. The rib 10 is preferably beveled 95 on its fore side, as indicated at 11, and straight on its rear side, as indicated at 12.

When the bullet is completely assembled, as shown in Fig. 2, the straight rear edge 12 of the rib 10 is embedded in the body of the 100 filler 2 and consequently prevents said filler from slipping forward relatively to the part 4 when said part expands, as indicated in Fig. 6. Moreover, the rear edge of the fore part 5 rests against the forward part of the 105 rib 10 and is held firmly thereagainst by the internal filler, so that at the moment of pene-

tration or impact, the rib 11 serves to sustain the point 5 of the bullet in its normal relation, and the momentum of the filler 2 in the rear part 4 is transmitted to the point. As shown clearly in Fig. 6, when the part 6 has expanded, the remainder of the bullet still retains its normal shape, its normal distribution of weight, and its normal penetrating point, and none of the marked distortion which occurs in the ordinary form of soft-nose bullet takes place in regard to the bullet of the present invention.

The modified construction illustrated in Figs. 7 and 8 is substantially the same as that illustrated in the preceding figures, except that the bevel 8^a of the fore part 6^a is continued backward to the rib 10^a and the rear end 14 of the fore end 5 is externally beveled to fit the beveled portion 8^a. At the forward end of the beveled portion of the fore part 5 an annular rib or shoulder 15 is provided and the extreme forward end of the rear part 4^a is continued forwardly beyond the shoulder 15 so as to provide an annular trough or forward projection which will serve to start the expanding action of the beveled end 6^a at the moment of penetration or impact. The form of bullet shown in Figs. 7 and 8 maintains its penetrating point and normal distribution of weight even after the beveled portion 6^a has expanded.

It will thus be seen that the rear parts 4 and 4^a at their forward edges or rims 6—6^a constitute a mushrooming member, which is attached to the body in such a manner, that when the point has penetrated an object beyond the free edge of the mushrooming members 6—6^a, such mushrooming member will be extended or expanded laterally. It will also be noted that the rib 9 may be dispensed with, it being essential, however to anchor the mushrooming member to the body of the bullet so that the free end or edge of the said member will be toward the penetrating point of the bullet. In this event, the forward edge of the same will be extended beyond the circumferential surface of the penetrating point so that the necessary obstruction will be offered to the object penetrated to cause the lateral extension or expansion of the mushrooming member.

What is claimed is:

1. A bullet having a hard metal penetrating point, a mushrooming member attached to the body with its free edge toward the point, and means carried by the body and co-operating with the free edge of the mushrooming member to cause the free edge to be laterally extended when the point has penetrated an object beyond the free edge of the mushrooming member.

2. A bullet having a body composed of a hard metal penetrating point and a butt composed of a soft metal of greater specific

gravity than the point, an expansible shell fitting upon the butt and extending beyond and exteriorly of the junction between the butt and point, and means carried by the body and co-operating with the forward edge of the shell to cause the forward edge of the shell upon penetration to expand laterally away from the body of the bullet to produce a mushroom.

3. A bullet having a two part jacket, the parts of which overlap with an exterior expansible rim toward the penetrating point of the bullet and extend beyond the circumferential surface of the fore part, and means carried by the fore part to cause a laterally expansible mushrooming of the expansible rim upon penetration.

4. A bullet having a hard metal penetrating point and a mushrooming member anchored at its rear end to the body of the bullet with its free end toward the point and exteriorly beyond the body, and means co-operating with the free end to cause the free end to extend laterally when the point has penetrated an object beyond the free end of the mushrooming member.

5. A bullet having a hard metal penetrating point and a mushrooming member provided with anchoring means disposed to project into and engage the body of the bullet, such mushrooming member having its free edge disposed toward the point, and means to co-operate with the free edge to cause such free edge to be laterally extended when the point has penetrated an object beyond the free edge of the mushrooming member.

6. A bullet having a hard metal penetrating point and a mushrooming member anchored at its rear end to the body of the bullet with its free end toward the point, whereby the free end is laterally extended when the point has penetrated an object beyond the free edge of the mushrooming member, the free edge of such mushrooming member being exteriorly of and beyond the circumferential surface of the bullet.

7. A bullet having a hard metal penetrating point and a mushrooming member provided with anchoring means disposed to project into and engage the body of the bullet, such mushrooming member having its free edge disposed toward the point, whereby the free edge is laterally extended when the point has penetrated an object beyond the free edge of the mushrooming member, the free edge of such mushrooming member being exteriorly of and beyond the circumferential surface of the bullet.

8. A bullet comprising a jacket made up of a relatively non-expanding body and a jacket comprising a fore and a rear part, the fore end of the rear part overlapping the outside of the rear end of the fore part and being adapted to expand under less resistance than is required to distort the body and

the fore part of the jacket, whereby said overlapping part can expand without producing expansion of the body and fore part.

9. A bullet comprising a two-part jacket 5 and a relatively non-expanding filler, the fore end of the rear part of the jacket overlapping the outside of the rear end of the fore part of the jacket and being adapted to expand under less resistance than is required 10 to distort the filler, whereby the overlapping portion of the rear part can expand without producing expansion of the filler.

10. A bullet comprising a relatively non-expanding filler and a jacket having a forwardly directed end adapted to expand under less resistance than is required to distort 15 the filler whereby the jacket can expand and the filler can retain its normal shape, and means for locking said filler and jacket 20 against separation after the jacket has expanded.

11. A bullet comprising a filler, a two-part jacket surrounding the filler, the rear part 25 of the jacket having an internal rib locking it to the filler, the rear end of the fore part of the jacket resting against said rib and the fore end of the rear part of the jacket overlapping the rear end of the fore part of the jacket and being adapted to expand under

less resistance than is required to distort the 30 filler.

12. A bullet comprising a two-part jacket, the rear part having a beveled fore end overlapping the outside of the rear end of the fore part, an internal rib in said rear part, 35 said rib having its fore face beveled and its rear face straight, the rear edge of the fore part of the jacket resting against said internal rib, and a filler in said chamber.

13. A bullet comprising a jacket formed 40 in two parts, the fore end of the rear part overlapping the outside of the rear end of the fore part, and being beveled to provide an expanding element, the rear part of the jacket having a filler opening therein, and 45 an internal rib having its rear face straight and its fore face beveled, the rear edge of the fore part of the jacket resting against said internal rib, and a filler in said jacket, 50 substantially as described.

In testimony that I claim the foregoing as my own, I have hereto affixed my signature in the presence of two witnesses.

ANDREW J. WATKINS.
